CLAIM

The ornamental design for a temple for spectacles, as shown and described.

DESCRIPTION

FIG. 1 is a perspective view of a temple for spectacles showing my new design;

FIG. 2 is a top plan view thereof;

FIG. 3 is a front elevational view thereof;

FIG. 4 is a left end elevational view thereof;

FIG. 5 is a right end elevational view thereof; and

FIG. 6 is a bottom plan view thereof.

The side opposite the side shown in FIG. 3 is a mirror image thereof.
